INTERNAL COMBUSTION ENGINE

Walts E. Hood, Harrison, Ark., assignor to Clarence N. Hudson, Harrison, Ark.

Application October 1, 1935, Serial No. 43,100

2 Claims. (Cl. 74—570)

My invention consists in a new and useful improvement in internal combustion engines and is designed to produce an engine in which the power shaft is a straight shaft without cranks being actuated by the engine pistons through eccentric driving means. The particular advantage of my improved engine is the elimination of vibration caused by the crank action of the usual type of engine, thereby producing smoothness of action 5 permitting considerably increased speed, with decreased wear. The particularly novel and useful feature of my invention is the means which I have devised for transmission of power from the pistons to the shaft, which comprises a series of eccentric 10 driving means actuated by the pistons and keyed upon the shaft. My improved means is so designed as to be readily assembled and disassembled, thus considerably simplifying mechanical work upon the engine, both in its construction 15 and repair.

While I have illustrated in the drawings filed herewith and have hereinafter fully described one specific embodiment of my invention, it is to be distinctly understood that I do not consider my 20 invention limited to said specific embodiment, but refer for its scope to the claims appended hereto.

In the drawings:

Fig. 1 is a side elevation, partly in section, on the line 1—1 of Fig. 2.

Fig. 2 is a transverse vertical section on line 2—2 of Fig. 1.

Fig. 3 is an enlarged end elevation of one of the eccentric driving means.

Fig. 4 is a vertical section on the line 4—4 of Fig. 3.

Fig. 5 is a side elevation of the eccentric driving plate.

Fig. 6 is a side elevation of the segmental locking plate.

Fig. 7 is a vertical section of the driving shaft.

As illustrated in the drawings, my improved engine has the motor block B and head B'. In this block B of the cylinders C with valves V and accompanying mechanism, and pistons P, the block B is supported by the engine frame F having the transverse beams F—1 on which is carried the shaft S in bearings S—1. It is to be especially noted (Fig. 1) that this shaft S is a straight shaft, entirely without cranks. The eccentric driving plates E are composed of two portions E—1 (Fig. 5) and E—2 (Fig. 6). The portion E—1 has an arcuate orifice O and two shoulders 1, 1. The portion E—2 has the two corresponding shoulders 2, 2. These portions are so designed that the portion E—1 may be placed upon the shaft S and

the portion E—2 may be bolted to the portion E—1 by bolts 3. The shaft S has chamfered portions S—2, so that when the portion E—2 is bolted to the portion E—1 the shoulders 2, 2 of the portion E—2 bear against the shoulders S—3 of the shaft S, provided by the chamfered S—2, and the shoulders 1, 1 of the portion E—1, as clearly illustrated in Fig. 3. Eccentric plates E are provided with suitable bearing rings E—3 formed in a plurality of segments and bolted to the plates E by the bolts 10 5. These rings E—3 have their rims E—4 formed substantially semi-circular in cross section. Disposed about each of these rings E—3 is a driving ring E—5 formed of two segments 6 having ears 7 and 8 connected by bolts 9 and 10 respectively. 15 The connecting rod 11 from each piston P has its lower end 12 received between the ears 8 of one of the rings E—5. This end 12 is slightly reduced to provide the shoulders 13 abutting against the ends of the ears 8. When the end 12 is so received, the bolt 10 is passed through the end 12 20 as well as the ears 8, thus fixing the connecting rod 11 to the ring E—5.

The frame F has orifices F—2 covered by the removable plates F—3. Suitably disposed beneath the frame F are the oil chambers F—4 into which the lower portions of the plates E, bearing rings E—3 and driving rings E—5 dip when operating, as illustrated in Figs. 1 and 2, thereby supplying splash lubrication to the upper parts. 30

From the foregoing description the details of construction of my engine, its use and operation will be obvious. It will be noted that for purposes of illustration in the drawings my engine has six cylinders, and that the cylinders C with their pistons P and their driving means to the shaft S are arranged in pairs (Fig. 1) and that the bearings S—1 are arranged between the pairs of driving units on the shaft S. Also it will be noted that I have arranged the driving units on the shaft S in such a way that there are two sets of three units each and that the eccentrics of each set are symmetrically disposed about the circumference of the shaft S. Thus, as shown in the drawings, the units I and VI have the same position, and the units II and V have the same position, and the units III and IV have the same position. It is this nicety of balance in the operating units about the shaft S, with the entire elimination of cranks from the shaft S, that produces the 40 elimination of vibration permitting high speed and reduction of wear.

It will be obvious that should repair or replacement of parts be required, access to the driving units may be had through orifices F—2, and dis- 55

assembled parts can be removed through said orifices F—2. All parts are so designed and related that the entire units, including the pistons P, can be removed through these orifices F—2.

Having described my invention, what I claim is:

1. In an internal combustion engine, the combination of a straight power shaft having chamfered portions to form a pair of shoulders defining chords on said shaft; a circular disc mounted on said shaft and comprising co-acting plates, one of said plates having a semi-circular orifice and a pair of straight shoulders, and the other plate having a pair of straight shoulders, the shoulders of the latter plate bearing upon the shoulders of the shaft and the shoulders of the former plate, a multi-piece collar bolted on the periphery of said disc; a grooved ring slidably embracing the periphery of said collar; and a connecting rod between said ring and the engine piston.
2. In an internal combustion engine, the combination of a straight power shaft having cham-

fered portions to form a pair of shoulders disposed at right angles to one another; a circular disc eccentrically mounted on said shaft and comprising co-acting plates, one of said plates having a semi-circular orifice and a pair of straight shoulders disposed at right angles to one another, and the other plate having a pair of shoulders disposed at right angles to one another, the first mentioned plate being received on the shaft with its orifice receiving therein the un-chamfered surface of the shaft and its shoulders aligned with the shoulders on the shaft, and the second mentioned plate being bolted to the first mentioned plate, its shoulders being received against the shoulders on the shaft and the first mentioned plate; a collar bolted on the periphery of said disc; a grooved ring embracing the periphery of said collar; and a connecting rod between said ring and the engine piston.

WALTS E. HOOD. 20
